Primary Examiner — Christian P. McLean*Assistant Examiner* — Jasmine L. Comedy(74) *Attorney, Agent, or Firm* — Craig A. Simmermon(57) **CLAIM**

The ornamental design for a roof tile, as shown and described.

DESCRIPTION

FIG. 1 is a top perspective view of a roof tile showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is an environmental perspective view thereof; and,

FIG. 9 is a bottom perspective view thereof.

The broken lines depict unclaimed environmental subject matter that forms no part of the claimed design.
